UNITED STATES PATENT OFFICE.

EDGAR E. ROBERTS, OF JACKSON, TENNESSEE, ASSIGNOR OF ONE-HALF TO HENRY DAMERELL, OF DETROIT, MICHIGAN.

TIE-PLATE.

1,172,391.

Specification of Letters Patent. Patented Feb. 22, 1916.

Application filed May 22, 1914. Serial No. 840,290.

To all whom it may concern:

Be it known that I, EDGAR E. ROBERTS, a citizen of the United States, and resident of Jackson, in the county of Madison and State 5 of Tennessee, have invented certain new and useful Improvements in Tie-Plates; and I do hereby declare that the following is a full, clear, and exact description thereof.

My invention has for its object to provide 10 a simple, economical and quickly adjusted cord fastener, the same being particularly adapted for tying packages and arranged with a view to utilizing such fasteners generally, in tying and wrapping, to thus avoid 15 knotting the cord.

It is obvious that the cord, in connection with the tie mechanism may be utilized indefinitely and, when worn, can be readily replaced.

20 The mechanism shown and described is especially adapted for use by railway mail clerks or the like in bundling letters, etc., but it is understood that the said tie may be utilized generally.

25 With the above objects in view the invention consists in certain peculiarities of construction and combination of mechanical parts as set forth hereinafter with reference to the accompanying drawings and subsequently claimed.

30 In the drawings Figure 1 represents a plan view of a tie-plate embodying the features of my invention, the same being shown with parts broken away and in section to 35 more clearly illustrate structural features and applied as a binder for a stack of letters, and Fig. 2, a sectional plan view of the same, the section being indicated by line 2-2 of Fig. 1.

40 Referring by characters to the drawings, 1 represents the cheek-piece of a tie-plate having a gripping foot 1' projecting therefrom, the same being provided with a central aperture whereby the thumb of the 45 operator, when placed upon the foot, will engage the surface thereunder and hold the plate in its proper position upon the face of the uppermost article of a stack to be tied.

The lower face of the tie-plate, as shown, 50 is uninterrupted, whereby it will snugly hug the surface upon which it is seated. The cheek-piece is apertured at one end for the reception of a cord A, which cord is secured within the aperture by knotting or any other 55 convenient method. The cheek-piece is pro-

vided with an overhanging lip 2, whereby a channel is formed between said lip and the opposite face of the cheek-piece. The channel is formed with an obliquely disposed rear wall 2' and fitted in the channel is a 60 movable jaw 3 having an oblique edge 3' that is adapted to have sliding engagement with the oblique channel-wall 2'. This jaw is also provided with an obliquely disposed slot 3'', into which is fitted a shoe 4, the said 65 shoe filling the space between the opposite faces of the cheek-piece and lip. This shoe is secured by rivets 5 as shown. The straight gripping face of the movable jaw is provided with serrations 6 and said gripping 70 face is arranged in approximate parallel relation to the opposite face of a fixed gripping jaw 7, the said jaw faces being upon a common plane. Projecting above the fixed gripping jaw 7 is a guide tongue 8, which 75 tongue, as shown, is upon a higher plane than the gripping faces of the jaws and is preferably grooved to form a cord seat.

While I have shown and described a shoe 80 for guiding the sliding or movable gripping jaw rectangular in shape, it is understood that circular pins may be substituted for the elongated shoe without departing from the spirit of my invention, and it is also manifest that there may be a slight space, in some 85 instances, between the rear face 3' of the jaw and channel shoulder 2', in which instance all of the strain placed upon the obliquely movable jaw will be resisted by the shoe.

90 In the operation of my device it is apparent that the tie-plate is placed in the position shown in Fig. 1 and, under ordinary conditions, the pad of the thumb of the left hand is fitted into the aperture of 95 the gripping foot, whereby the plate is rigidly held in its correct position. The cord which projects from the cheek-piece is then wrapped in a longitudinal direction about the bundle and inserted in the channel of 100 the guide-tongue 8, whereby a stay-corner for the cord is formed. The cord is thereafter looped about the bundle at a right-angle to the first loop and the free end of 105 said cord is then drawn downward in the groove formed by the gripping faces of the fixed and movable jaw members. The free end is thus seated upon a lower plane than that section of the cord which is fitted in 110 the guide-tongue and, after pulling the free

end of the cord in the direction indicated by the arrow, it is apparent that all of the slack in said cord is taken up and that the bundle is tightly bound. This forward draw of the free end of the cord will cause the sliding jaw 3 to move in the same direction slightly and when said free end is released, tension of the cord in retracting will cause the slideable jaw to move with the cord and thus the gripping faces of the jaws will be brought together to firmly lock the confined end of the cord in the position shown. It is obvious that, to release the tie, the cord is pulled in the same direction as indicated by the arrow, whereby the movable jaw will release its grip and thereafter the cord can readily be removed.

It is also obvious that I may, without departing from the spirit of my invention, if desired, employ a spring in connection with the hinge jaw, whereby it will be positively forced into a cord-gripping position with relation to the fixed jaw.

From the foregoing description it will be seen that a simple and effective tie-plate is produced wherein bundles or letters can be quickly confined by a cord or freed from said cord with a maximum speed, it being borne in mind that in the mail service, for example, speed in such matters is an important item.

It is also obvious that, while I have shown a tie-plate in approximate proportions, said proportions may be varied indefinitely without departing from the scope of my invention.

Copies of this patent may be obtained for five cents each, by addressing the "Commissioner of Patents, Washington, D. C."

I claim:

1. A cord tie comprising a base having one end portion provided with a cord-end engaging slot, said base having a slot extending transversely thereacross, one wall of the slot being obliquely disposed and provided with an overhanging lip, a wedge guide in the slot beneath the lip, a slideable wedge in the channel and having a slot in its rear wall that is engaged by the guide, the opposite side wall of the channel forming a stationary gripping jaw that co-operates with the wedge to engage a cord and above said stationary jaw, the wall of the channel being provided with a cord-receiving groove.

2. A package tie comprising a base provided with a knot-engaging portion at one end, said base having a transversely extending channel formed therein, one wall of said channel being oblique and provided with an overhanging lip, the opposite wall of said channel having a gripping surface and above and parallel with the said gripping surface being provided with a cord-receiving groove, and a movable jaw mounted within the channel under the lip thereof and co-operating with the gripping surface.

In testimony that I claim the foregoing I have hereunto set my hand at Jackson in the county of Madison and State of Tenn., in the presence of two witnesses.
